GEORGE B. METZ, OF WESTWOOD, NEW JERSEY, ASSIGNOR TO GLEASON-TIEBOUT GLASS COMPANY, OF NEW YORK, N. Y., A CORPORATION OF NEW YORK

DESIGN FOR A LIGHTING FIXTURE GLOBE

Application filed September 17, 1932. Serial No. 44,985. Term of patent 7 years.

To all whom it may concern:

Be it known that I, GEORGE B. METZ, a citizen of the United States of America, residing at 24 Clinton Avenue, Westwood, Bergen County, New Jersey, have invented a new, original, and ornamental Design for a Lighting Fixture Globe, of which the following is a specification, reference being had to the drawing, forming a part thereof.

Fig. 1 is a top plan view of a lighting fixture globe, showing my new design.

Fig. 2 is a side elevation of the same.

I claim:

The ornamental design for a lighting fixture globe, as shown.

GEORGE B. METZ.
